UNITED STATES PATENT OFFICE

2,455,288

UMBRELLA

Octavio Jose Alvarez, New York, N. Y., assignor
to Alvarez Patent Corporation, New York, N. Y.

Application September 18, 1946, Serial No. 697,683

11 Claims. (Cl. 135—20)

1

My present invention relates to new and useful improvements in umbrellas and more particularly to umbrellas of a type suitable for manufacture and sale at a low price for emergency purposes.

This invention has for one of its objects the provision of an improved emergency umbrella.

Another object of the present invention consists of an emergency umbrella which may be manufactured at a low cost, is compact when folded and takes a preferably substantially rectangular shape when opened.

A further object of my present invention is to provide an emergency umbrella which will be rigid and efficient when opened for use and can be conveniently carried in folded position.

Still another object of my present invention consists of an umbrella which can be easily and quickly assembled.

Finally, it is also an object of my present invention to provide an emergency umbrella which will be durable, efficient and convenient to use as is consistent with the inexpensive manufacture necessary in an article which should be adapted to serve its purpose for a comparative short time only and then be discarded.

With the above objects in view an emergency umbrella according to my present invention comprises in combination a plurality of several elements, viz., a supporting structure composed of a plurality of supporting rib members having each an outer and an inner end and connected at their inner ends to each other so as to be foldable between inoperative position folded flat into one plane and operative open position with their outer ends spaced from each other, an umbrella rod constructed so as to be attachable to the above defined supporting rib members at their connected inner ends and to be easily detachable therefrom, and an umbrella cover constructed so as to be easily attachable to the outer ends of the supporting rib members mentioned above when the same are in operative open position and to be easily detachable therefrom, whenever desired.

Preferably the umbrella cover has a plurality of corners the number of which is equal to the number of the outer ends of the rib members and is constructed so as to be easily attachable at these corners to the outer ends of the rib members in the manner set forth above.

2

In accordance with a preferred embodiment of my present invention I provide an umbrella which comprises in combination four supporting rib members of the above type, an umbrella rod attachable to these rib members as set forth above and an umbrella cover having four corners and constructed so as to be easily attachable at these four corners to the outer ends of the four rib members supporting the cover.

10 I have found it advisable to provide at the outer ends of the supporting rib members a plurality of so-called first attaching means which are adapted to co-operate with and engage a plurality of so-called second attaching means provided on the umbrella cover at the edge of the same.

I wish to stress that it is an important feature of my present invention that the above second attaching means are arranged on the umbrella cover in such a manner that they are adapted to engage the first attaching means at the ends of the supporting rib members only when these supporting rib members are in open position with their outer ends spaced from each other; in this manner the cover itself is holding the supporting rib members in operative open position preventing unintentional folding of the same into the inoperative folded position defined above.

An emergency umbrella of a particularly simple construction consists in accordance with my present invention of a plurality, preferably two flat supporting rib members having each two outer ends and a central rib portion, means connecting these flat supporting rib members at their central rib portions to each other so that they are foldable about these connecting means between inoperative folded position superimposed upon each other and operative open position with their outer ends spaced from each other, an umbrella rod of the above defined type, and an umbrella cover constructed so as to be easily attachable in the manner set forth above to the outer ends of the flat supporting rib members when the same are in operative open position.

45 The novel features which I consider as characteristic for my invention are set forth in particular in the appended claims. The invention itself, however, both as to its construction and its method of operation, together with additional objects and advantages thereof, will be best un-

derstood from the following description of specific embodiments when read in connection with the accompanying drawings, in which:

Fig. 1 is a perspective view of the supporting structure of an umbrella according to my present invention, in inoperative folded position;

Fig. 2 is a perspective view of the supporting structure shown in Fig. 1, in operative open position;

Fig. 3 is a perspective view of an umbrella cover adapted to be used in combination with the supporting structure shown in Figs. 1 and 2;

Fig. 4 is a perspective view of an umbrella rod adapted to be used in combination with a supporting structure shown in Figs. 1 and 2;

Fig. 5 is an umbrella composed of umbrella parts shown in Figs. 1 to 4, in operative open position; and

Fig. 6 is a perspective view of the umbrella shown in Fig. 5 in disassembled packed position.

As shown in Figs. 1 and 2, the supporting structure of an umbrella according to my present invention preferably consists of two flat supporting rib members 10 and 11 having each two outer ends 12, 13 and 14, 15, respectively. These flat supporting rib members 10 and 11 are made preferably of a bendable sheet material, e. g., cardboard or a resilient plastic substance.

As shown in Figs. 1 and 2, the two supporting rib members 10 and 11 are connected to each other at the central rib portions 16 by two rows of staples 17 and 18.

Furthermore, I provide at the outer ends 12, 13, 14 and 15 of the supporting rib members 10 and 11 projecting portions 19, 20 and 21, 22, respectively, serving as so-called first attaching means for securing the umbrella cover 23 shown in Fig. 3 to the outer ends of the supporting structure.

The umbrella cover 23 is preferably rectangular and provided at each of its corners with an eyelet 24 serving as so-called second attaching means and adapted to engage the corresponding projecting portions 19, 20, 21 and 22 arranged at the outer ends of the flat supporting rib members 10 and 11.

The cover 23 is shaped so that its length is smaller than the length of the supporting rib member 10 and 11 when the same are in unfolded position shown in Fig. 1. However, the distance between the four corners of cover 23 and the eyelet 24 arranged at these corners is chosen so that these eyelets are adapted to engage the projecting portions 19, 20, 21 and 22 if the supporting rib members 10 and 11 are in the operative open position shown in Fig. 2.

The umbrella rod 25, shown in Fig. 4, is preferably made also of a cardboard or a plastic sheet material and provided at its top with a narrow projecting portion 27 fitting into the slot 28 created by the connecting staples 17 and 18 between the two flat supporting rib members 10 and 11.

My new umbrella is assembled as shown in Fig. 5:

First the supporting structure is bent from its inoperative folded position shown in Fig. 1 into the operative open position shown in Fig. 2.

Then the umbrella cover 23 is unfolded and the eyelets 24 are slipped, as shown in Fig. 5, over the corresponding projecting portions 19, 20, 21 and 22 arranged at the corresponding outer ends 12, 13, 14 and 15, respectively, of the flat supporting rib members 10 and 11.

Then the upper narrow portion 27 of the umbrella rod 25 is pushed into the slot 28 between the two flat supporting rib members 10 and 11. In this position the umbrella is ready for use.

As the umbrella cover 23 is adapted to engage the projecting portions at the outer ends of the rib members 10 and 11 only if the same are in open position, it is impossible that these rib members move from open position into folded position while the umbrella cover engages their outer ends.

After use it is possible to either discard the entire umbrella or to fold it into a compact package as shown in Fig. 6.

It will be understood that each of the elements described above, or two or more together, may also find a useful application in other types of umbrellas differing from the type described above.

While I have illustrated and described the invention as embodied in discardable emergency umbrellas, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention, and, therefore, such adaptations should and are intended to be comprehended within the meaning and range of equivalence of the following claims.

What I claim as new and desire to secure by Letters Patent is:

1. An umbrella comprising a supporting structure composed of a plurality of supporting rib members having outer and inner portions and connected at their inner portions to each other so as to be movable between inoperative position arranged flat in substantially one plane and operative open position with their outer portions spaced from each other; an umbrella rod constructed so as to be attachable to said supporting rib members at said connected inner portions of the same and to be easily detachable therefrom; and an umbrella cover constructed so as to be easily attachable to said outer portions of said supporting rib members when the same are in said operative position and to be easily detachable therefrom, whenever desired.

2. An umbrella comprising a supporting structure composed of four supporting rib members having outer and inner portions and connected at their inner portions to each other so as to be movable between inoperative position arranged flat in substantially one plane and operative open position with their outer portions spaced from each other; an umbrella rod constructed so as to be attachable to said four supporting rib members at said connected inner portions of the same and to be easily detachable therefrom; and an umbrella cover constructed so as to be easily attachable to said four outer portions of said four supporting rib members when the same are in said operative position and to be easily detachable therefrom, whenever desired.

3. An umbrella comprising a supporting structure composed of a plurality of supporting rib members having outer and inner portions and connected at their inner portions to each other so as to be movable between inoperative position arranged flat in substantially one plane and operative open position with their outer ends spaced

from each other; an umbrella rod constructed so as to be attachable to said supporting rib members at said connected inner portions of the same and to be easily detachable therefrom; and an umbrella cover having a plurality of corners, and constructed so as to be easily attachable at each of said corners to one of said outer portions of said supporting rib members when the same are in said operative position and to be easily detachable therefrom, whenever desired.

4. An umbrella comprising a supporting structure composed of a plurality of supporting rib members having each an outer and an inner portion and connected at their inner portions to each other so as to be movable between inoperative position arranged flat in substantially one plane and operative open position with their outer portions spaced from each other; an umbrella rod constructed so as to be attachable to said supporting rib members at said connected inner portions of the same and to be easily detachable therefrom; an umbrella cover; and attaching means provided on said umbrella cover constructed so as to be easily attachable to said outer portions of said supporting rib members when the same are in operative position and to be easily detachable therefrom, whenever desired.

5. An umbrella comprising a supporting structure composed of a plurality of supporting rib members having outer and inner portions and connected at their inner portions to each other so as to be movable between inoperative position arranged flat in substantially one plane and operative open position with their outer portions spaced from each other; an umbrella rod constructed so as to be attachable to said supporting rib members at said connected inner portions of the same and to be easily detachable therefrom; an umbrella cover having a plurality of corners; and attaching means secured to said umbrella cover at each of said corners of the same and constructed so as to be easily attachable to said outer portions of said supporting rib members when the same are in said operative position and to be easily detachable therefrom, whenever desired.

6. An umbrella comprising a supporting structure composed of a plurality of supporting rib members having outer and inner portions and connected at their inner portions to each other so as to be movable between inoperative position arranged flat in substantially one plane and operative open position with their outer ends spaced from each other; an umbrella rod constructed so as to be attachable to said supporting rib members at said connected inner portions of the same and to be easily detachable therefrom; an umbrella cover; a plurality of first attaching means arranged at said outer portions of said supporting rib members; and a plurality of second attaching means provided on said umbrella cover and constructed so as to easily engage said first attaching means at said outer portions of said supporting rib members when the same are in operative position and to be easily disengaged from the same, whenever desired.

7. An umbrella comprising a plurality of flat supporting rib members having each two outer ends and a central rib portion; means connecting said flat supporting rib members at said central rib portions of the same to each other so that said flat supporting rib members are foldable about said connecting means between inoperative position arranged flat in substantially one plane and operative position with their outer ends

spaced from each other; an umbrella rod constructed so as to be attachable to said flat supporting rib members at said connected central rib portions of the same and to be easily detachable therefrom; and an umbrella cover constructed so as to be easily attachable to said outer ends of said flat supporting rib members when the same are in said operative position and to be easily detachable therefrom, whenever desired.

10 8. An umbrella comprising two flat supporting rib members having each two outer ends and a central rib portion; means connecting said two flat supporting rib members at said central rib portions of the same to each other so that said two flat supporting rib members are foldable about said connecting means between inoperative position superimposed upon each other and operative position with their outer ends spaced from each other; an umbrella rod constructed so as to be attachable to said two flat supporting rib members at said connected central rib portions of the same and to be easily detachable therefrom; and an umbrella cover constructed so as to be easily attachable to the outer ends of said two flat supporting rib members when the same are in said operative position and to be easily detachable therefrom, whenever desired.

15 9. An umbrella comprising a plurality of flat supporting rib members having each two outer ends and a central rib portion; means connecting said flat supporting rib members at said central rib portions of the same to each other so that said flat supporting rib members are foldable about said connecting means between inoperative position arranged flat in substantially one plane and operative position with their outer ends spaced from each other; an umbrella rod constructed so as to be attachable to said flat supporting rib members at said connected central rib portions of the same and to be easily detachable therefrom; and an umbrella cover having a plurality of corners the number of which is equal to the number of said outer ends of said flat supporting rib members and constructed so as to be easily attachable at each of said corners to one of said outer ends of said flat supporting rib members when the same are in said operative position and to be easily detachable therefrom, whenever desired.

20 45 10. An umbrella comprising a plurality of flat supporting rib members having each two outer ends and a central rib portion; means connecting said flat supporting rib members at said central rib portions of the same to each other so that said flat supporting rib members are foldable about said connecting means between inoperative position arranged flat in substantially one plane and operative position with their outer ends spaced from each other; an umbrella rod constructed so as to be attachable to said flat supporting rib members at said connected central rib portions of the same and to be easily detachable therefrom; an umbrella cover; and four attaching means secured to said umbrella cover and constructed so as to be easily attachable to the outer ends of said two flat supporting rib members when the same are in said operative position and to be easily detachable therefrom, whenever desired.

25 55 60 65 70 75 11. An umbrella comprising two flat supporting rib members having each two outer ends and a central rib portion; means connecting said two flat supporting rib members at said central rib portions of the same to each other so that said two flat supporting rib members are fold-

7
able about said connecting means between in-operative position superimposed upon each other and operative position with their outer ends spaced from each other; an umbrella rod constructed so as to be attachable to said two flat supporting rib members at said connected central rib portions of the same and to be easily detachable therefrom; an umbrella cover; four first attaching means each arranged at the outer end of one of said two flat supporting rib members; and four second attaching means secured to said umbrella cover and constructed so as to easily engage said four first attaching means at the outer ends of said two flat supporting rib
10

members when the same are in said operative position and to be easily detachable therefrom, whenever desired.
